UNITED STATES PATENT OFFICE.

EDWARD BEACH, OF ILION, NEW YORK, ASSIGNOR TO REMINGTON ARMS COMPANY, OF ILION, NEW YORK.

EJECTOR MECHANISM FOR FIREARMS.

SPECIFICATION forming part of Letters Patent No. 763,458, dated June 28, 1904.

Application filed May 2, 1903. Serial No. 155,285. (No model.)

To all whom it may concern:

Be it known that I, EDWARD BEACH, of Ilion, in the county of Herkimer and State of New York, have invented certain new and useful Improvements in Ejector Mechanisms for Firearms; and I do hereby declare that the following is a full, clear, and exact description of the invention, which will enable others skilled in the art to which it appertains to make and use the same, reference being had to the accompanying drawings, and to the figures of reference marked thereon, which form part of this specification.

The object of my present invention is to provide an improved ejector mechanism for firearms which simply and effectively accomplishes its object and in a new and novel manner.

In the drawings, Figure 1 shows the working parts of a firearm embodying the features of my invention, mostly in vertical section, with the parts in the closed position. Fig. 2 shows substantially the same parts as Fig. 1 in a partially-open position. Fig. 3 shows the same as Fig. 2 in the completely-open position. Fig. 4 shows a cross-section taken on line A B of Fig. 1.

Referring to the reference letters and figures in a more particular description, 1 indicates the frame, which includes, among other things, the standing breech 2 and the forwardly-extending portion 1^a, carrying in the forward end the joint-pin 3. The barrel 4 is provided, as usual, with a barrel-lug 5 on the under side, which is received in a recess in the forward portion 1^a of the frame and engages on the joint-pin 3. For securing the barrel in closed position with reference to the frame there is provided a catch 5^a, engaging with a shoulder on the barrel-lug and operated by the usual top lever 6. In the barrel-lug there is provided a longitudinal opening parallel with the barrel which receives the ejector-slide 7, carrying the ejector-head 8, which head is adapted to engage with the rim of the shell in the barrel. The ejector is retained in position in the arm by the transverse pin 9 passing through the barrel-lug and engaging in a recess in the under side of the stem or slide 7,

which recess is elongated to permit the movement of the ejector. In the opening which receives the ejector-slide 7 there is also mounted to slide freely to and fro the ejector-striker 10. Farther back in the opening which receives the striker 10 is the spring 11 for operating the striker. The striker 10 is provided with a shoulder adapted to be engaged by the shoulder of the catch 12. The catch 12 is jointed at 13 to the frame at a point substantially in a vertical line below the joint-pin 3. A spring 14, supported on a pin in the barrel-lug, serves to force the free end of the catch 12 upward into engagement with the shoulder of the striker when it is not otherwise forced down.

Mounted on a transverse pin or pivot 15 in the barrel-lug is the starting and tripping lever 16. This lever has one arm adapted to engage with the rear end of the ejector-slide, a shoulder adapted to engage with a shoulder on an arm of the catch 12, and also an arm adapted to engage on the upper side of the said arm of the catch 12 and trip the same.

The operation of the mechanism is substantially as follows: Starting with the parts in the position in which they are shown in Fig. 1, after withdrawing the catch 5^a by means of the top lever 6 the arm can be broken down or turned on the joint-pin 3 in the usual manner. During the first part of the operation and by reason of the peculiar arrangement of the joint 13 of the catch 12 and the pivot-pin 3 the catch-lug 12 is moved forward with reference to the barrel-lug. In so doing the shoulder on the end of the catch 12 engages with the shoulder on the starting and tripping lever, causing the tripping-lever to turn on its pivot to some extent. In so doing the arm which is in engagement with the ejector-slide forces the ejector and starts the cartridge-shell. As the movement is continued the tripping-arm of the lever 16 engages on the top of the arm of the catch 12 and forces it downwardly until such time as the catch-shoulder becomes disengaged from the shoulder on the striker 10. When the striker is thus released, it is instantly propelled toward the rear, striking the ejector

and instantly expelling the shell. During the first part of the opening operation the striker is drawn back to some extent, following the movement of the catch 12; but this only increases the amount of the stroke after it is released. In closing the arm the ejector is cammed back into its closed position by engaging with and sliding down the standing breech 2. It at the same time forces back the striker 10 until such time as it is caught by the catch 12 and held. In the end of the arm of the catch 12 there is provided an adjusting-screw 17, which is engaged by the tripping-arm of the lever 16, and by adjusting this screw the ejecting operation can be timed.

What I claim as new, and desire to secure by Letters Patent, is—

1. The combination with the working parts of a breakdown firearm including a barrel-lug of a sliding ejector mounted in the barrel-lug, a striker therefor, a spring for operating the striker, a catch for holding the striker jointed to the frame adjacent to the joint-pin and a

starting and tripping lever pivoted in the barrel-lug having an arm to engage the ejector, 25 an arm and shoulder to engage and trip the said striker-catch, substantially as set forth.

2. The combination in a firearm of the frame having a standing breech and a forward extension therefrom supporting the joint-pin, a 30 barrel and barrel-lug hinged on the joint-pin, an ejector mounted on a slide in the barrel-lug, a sliding striker with its operating-spring, a striker-catch jointed to the frame adjacent to the joint-pin and a starting and tripping lever pivoted in the barrel-lug having an arm to engage the ejector and a shoulder and arm to engage and trip the striker-catch, substantially as set forth.

In witness whereof I have affixed my signature, in presence of two witnesses, this 29th day of April, 1903.

EDWARD BEACH.
